FUEL INJECTION SYSTEM

Ben G. Parsons, Grosse Pointe, Mich.

Application January 2, 1948, Serial No. 335

7 Claims. (Cl. 123—139)

1

This invention relates to improvements in fuel injection systems and more particularly to improvements in gasoline fuel injection systems for multi-cylinder engines.

One of the primary objects of the present invention is to provide improvements in systems of the type mentioned wherein gasoline may be distributed to a multiplicity of cylinders in a system employing a single pump and distributor.

A further object of the invention is to provide improvements in systems of the type mentioned wherein the pump may be mounted in any convenient location and does not need to be mounted closely adjacent the engine cylinders and the necessity of a transfer pump is eliminated.

A further object of the invention is to provide improvements in systems of the type mentioned wherein means is provided which is responsive to the engine manifold pressure so as to vary the output of the aforementioned fuel pump.

A still further object of the invention is to provide improvements in systems of the type mentioned wherein there will be high delivery at low manifold pressure and low delivery at high manifold pressure.

A still further object of the invention is to provide, in the aforementioned manifold pressure responsive means, a high engine speed adjustment, and idling speed adjustment.

Other objects of the invention will become apparent from the following specification, the drawings relating thereto, and from the claims hereinafter set forth.

In the drawing in which like numerals are used to designate like parts in the several views throughout:

Figure 1 is a diagrammatic view of the fuel injection system according to the present invention and showing the pump, distributor, and pressure responsive means, and the relation of the same to each other and to the fuel tank and injector nozzles; and

Fig. 2 is a vertical cross sectional view of the distributor employed in Fig. 1.

Referring to the drawing, a fuel supply tank is indicated at 3 having a pump generally indicated at 5 mounted thereon. The pump is connected to a distributor generally indicated at 7 through a flexible conduit 9, and the distributor is connected to a plurality of injector nozzles 11 through flexible conduits 13. The nozzles 11 may be of the type disclosed in the copending application of Ben G. Parsons, Serial No. 546,352, filed July 24, 1944, now abandoned, or may be an open end tube.

The pump 5 comprises a housing 15 formed with a longitudinally extending inlet passageway 17. An inlet port 19 is located intermediate the ends of the housing 15 and communicates with the inlet

2

passageway 17 and also communicates through an inlet tube 21 with the interior of the tank 3. The tube 21, of course, extends to a position adjacent the bottom of the tank 3.

5 A pair of longitudinally extending and intersecting bores 23 and 25 are also formed in the housing 15 above the passageway 17. The passageway 17 and the bores 23 and 25 extend through the ends of the housing 15 within recessed portions 27 and 29. An end plate 31 is fixed to one end of the housing and forms, between the inner face thereof and the recess 27, an inlet chamber communicating the adjacent end of the passageway 17 with the adjacent ends of the bores 23 and 25. An end member 33 is removably attached to the opposite end of the housing 15 and is spaced from the recess 29 to provide an inlet chamber between the inner face thereof and recess 29 which communicates with that end of the passageway 20 17 and with the adjacent ends of bores 23 and 25.

A pair of intermeshing pump elements 35 and 37 are disposed within the bores 23 and 25 respectively. Each of the pump elements 35 and 37 is threaded with a lead extending from the outer 25 ends of the elements toward the center thereof where the threads open into reduced portions 39 and 41. The outer ends of the threads of the pump elements communicate with the inlet chambers opposite the ends of the housing 15. The reduced portions 39 and 41 form with the adjacent peripheries of the bores 23 and 25 an outlet chamber which communicates through an outlet port 43 with conduit 9 which is attached to the housing 15 adjacent the outlet 43 by means of a fitting 44.

One of the pump elements, for example, element 35, is driven by an electric motor 45 which is connected to the end member 33. The motor has its drive shaft received within a suitable bearing mounted in the member 33 in axial alignment with the element 35. The motor shaft is 40 coupled to an inwardly projecting end 49 of the element 35 by means of a coupling indicated at 51.

A manifold pressure responsive unit, generally indicated at 53, is provided for controlling the speed of the motor 45. The unit 53 consists of a hollow housing 55 having an enlarged recess 57 formed in one end thereof. The wall of the housing 55, at the enlarged end thereof, is formed with an outturned annular flange 59. An end cap 61 is secured to the enlarged end of the housing 55 by means of a reversely bent annular flange 63, which embraces the housing flange 59. The end cap 61 is formed with an outwardly projecting, externally threaded, hollow nipple 65 which has 55 a central aperture 67 in the end wall thereof. The nipple 65 is adapted to be threaded into an opening in an engine manifold so as to connect the housing to the latter. A calibrated, bellows-type diaphragm 69 is disposed within the enlarged

housing recess 57 and has one end thereof fixedly secured to the inner face of the end cap 61, in alignment with the aperture 67 of the nipple 65. A rheostat 70, which includes an electrically conductive metallic rod 71 is secured to the opposite end of the diaphragm 69, and is insulated therefrom by suitable insulation 73. The remote end of the shaft 71 is embraced by a winding of wire 75 so as to form the rheostat 70, which is disposed centrally within the housing 55. Other forms of rheostats may be employed, the specific one shown being for the purpose of illustration.

An end cap 77 is threadably connected to the small end of the housing 55 and is provided with an outwardly projecting central boss 79, having an aperture 81 therethrough. A pin or stud 83 has its inner end fixedly connected to the adjacent end of the rheostat 70. Suitable insulating material 85 insulates the end of the pin 83 from the rheostat. A coil spring 87 surrounds the inner end of the pin 83 and has its inner end abutting the end of the rheostat 70, and its outer end abutting the end wall of the cap 77. The outer end of the pin 83 projects outwardly through the central aperture 81 of the end cap boss 79 and is threaded at 89. A hollow, elongated, nutlike member 91 is threadably connected to the outer end of the pin 83, and the inner end of the member 91 is formed with an enlarged recess 93. The outer end of the end cap boss 79 is disposed within the recess 93 and formed with an outturned flange 95, which slidably engages the wall of the recess 93. Thus the member 91 can slide longitudinally with respect to the end cap 77, and can be adjusted with respect thereto by threading it inwardly or outwardly on the pin 83.

A pair of longitudinally spaced stationary contacts 99 and 101 are disposed within the housing 55 so as to engage the rheostat 70. The stationary contact 99 is connected to one terminal of the electric motor 45 by means of a wire 103 and battery 105. The contact 101 is connected to the opposite terminal of the motor 45 through a wire 107. The wire 107 is provided with a switch 109 which closes only when the engine ignition is turned on, and is open when the same is off. A second switch 111 is provided in line 107 which closes when the engine is started and a predetermined engine oil pressure obtained. In this way the motor 45 will not be operated unless the ignition is on, and the engine is actually started, and oil pressure obtained.

The distributor 7 comprises a housing 113 having a central aperture 115 extending longitudinally therethrough and a distributor plate 116 connected to one end face thereof. The plate 116 is provided with an inlet port 117 which communicates with the housing central aperture 115, and with the conduit 9 through a fitting 119. A distributor element 121 is disposed within the housing aperture 115, and rotatably supported in the housing by bearing 123 and snap ring 125. One end of the distributor element 121 is provided with a universal coupling 129 for connection with suitable drive means, such as the engine cam shaft for properly timing the distribution of the fuel to the cylinder. The distributor element 121 is provided at the opposite end from the coupling 129 with a central longitudinally extending recess 131 which communicates with the inlet port 117, so as to be filled with the fuel from the pump 5. The wall of the distributor element 121 is provided with an opening 133 which communicates with the recess 131. A plurality of circumferentially, equally spaced passageways 135

are provided in housing 113 which communicates singly with the distributor opening 133, during rotation of the distributor element 121. The housing passageways 135 communicate with outlet ports 137 in the distributor plate 116 secured to the end face of the housing 113. The outlet ports 137 communicate with the conduits 13 through suitable fittings so that upon rotation of the distributor element 121 by, for example, the cam shaft of the engine, the fuel will be discharged through the outlet ports 137 to the nozzles 11, in timed relation to the engine so as to properly inject the fuel into the cylinders at the proper time. A groove 140 is provided in the housing, around the aperture 115, for trapping any leakage of fuel and a conduit 141 communicates with the groove 140 and is connected to the intake air manifold. In this way this small amount of fuel is sucked into the manifold by vacuum so as to obviate fuel losses. The wall of the rotary distributor 121 is relatively thin so that it will expand under internal pressure against the wall of the bore preventing leakage. Also, the wall can contract to prevent sticking.

In operation of the system above described the distributor element 121 is driven in timed relation from the engine cam shaft, for example, and the motor 45 is operated at the proper operating speed by the unit 53. When the engine is at idling speed, the manifold pressure is at its lowest point and the manifold vacuum at its highest point so that the diaphragm bellows 69 of the unit 53 is collapsed and the rheostat 70 will move to the right, as viewed in Fig. 1, due to the spring 87. When the rheostat 70 moves to the right the winding 75 will increase the resistance between the stationary contacts 99 and 101 and cause the speed of the motor 45 to be reduced to its minimum, so that the fuel delivery from the pump 5 to the distributor 7 is at a minimum. The amount of movement to the right of the rheostat 70 can be adjustably controlled by means of the nutlike element 91. By threading the nut element 91 inwardly or outwardly on the pin 83, the movement to the right of the rheostat 70 can be controlled. As the nutlike member 91 moves with the pin, it will abut the outer face of the end cap 77 in accordance with its threaded position on the pin 83, so that the minimum speed of motor 45, for idling speed of the engine can be properly adjusted.

When the engine is running at wide open throttle, the manifold pressure is at a maximum and the manifold vacuum at a minimum so that the diaphragm bellows 69 is expanded its full amount, thus moving the rheostat 70 to the left as viewed in Fig. 1, and reducing the resistance between the stationary contacts 99 and 101. This causes the motor 45 to rotate at its maximum speed so that the maximum fuel delivery from the pump 5 to the distributor 7 is obtained. The amount of movement of the rheostat 70, to the left, can be controlled by threadably adjusting the end cap 77 on the housing 55 so as to vary the value of the spring 87. In this way the maximum speed of the motor 45, for high speeds of the engine can be adjustably controlled to insure the proper fuel delivery for wide open throttle of the engine. The bellows 69, of course, will expand or collapse in varying degrees between engine idling speed and wide open throttle, so as to automatically synchronize the speed of the motor 45 and therefore the fuel delivery from the pump to the distributor, in accordance with the manifold pressure.

The operation of the motor 45 at the proper speed causes rotation of the intermeshing pump elements 35 and 37, and withdraws gasoline from the tank 3 through the inlet port 19 into the passageway 17. The fluid passes toward both ends of the passageway into the inlet chambers around the opposite ends of the pump elements 35 and 37. The fluid is pumped into the outlet chamber surrounding the reduced portions 39 and 41 and out through the outlet port 43 under pressure into the distributor inlet port 117, through the conduit 9. Since the pressure adjacent the end members 31 and 33 is under atmospheric pressure there will be no leakage of fuel through these parts. Furthermore, when the pump is not operating the fluid will merely drain back under no pressure to passageway 17 and back through the tank.

As the distributor element 121 rotates, the fluid under pressure is supplied through the distributor opening 133 and the passageways 135 to the outlet ports 137, and therefore to each of the cylinders associated with the nozzles 11 in succession.

In certain instances it may be desirable to have the device sensitive to the engine speed as well as the manifold pressures. This may be accomplished by loading the spring 87 through the action of a governor suitably connected to a speed responsive element on the engine or by raising or lowering the distributor plunger 121 through the action of the governor. In this case the opening 133 would be tapered on the longitudinal axis rather than round.

Formal changes may be made in the specific embodiment of the invention described without departing from the spirit and substance of the invention, the scope of which is commensurate with the appended claims.

I claim:

1. In a fuel injection system for a manifold-type engine, an injection nozzle, a fuel distributor connected to said nozzle, a fuel pump connected to said distributor, variable speed drive means independent of the speed of the engine for driving said pump, and means responsive to manifold pressure for varying the driving speed of said drive means.

2. In a fuel injection system for a manifold-type engine, an injection nozzle, a fuel distributor connected to said nozzle, a fuel pump connected to said distributor, variable speed drive means independent of the speed of the engine for driving said pump, and means responsive to manifold pressure for varying the driving speed of said drive so as to increase the pump output at high manifold pressure and decrease the pump output at low manifold pressure.

3. In a fuel injection system for a manifold-type engine, a multiplicity of injection nozzles, a conduit connected to each nozzle, a fuel distributor having outlet ports communicating with the conduits, said distributor having an inlet port, means communicating said inlet port with said outlet ports in succession, a fuel pump separate from said distributor, a conduit connecting the pump outlet with said distributor outlet, an electric motor independent of the speed of said engine driving said pump, and means responsive to manifold pressures for varying the speed of said electric motor independently of engine speed whereby to increase the speed of said motor at high manifold pressures and decrease the speed of said motor at low manifold pressures.

4. In a fuel injection system for a manifold-

type engine, an injection nozzle, a fuel distributor connected to said nozzle, a fuel pump connected to said distributor, an electric motor independent of the speed of said engine driving said pump, variable impedance means for varying the speed of said electric motor, and diaphragm means operatively connected to said variable impedance means and responsive to manifold pressures for varying said impedance means and therefore the speed of said electric motor independent of the speed of said engine.

5. In a fuel injection system for a manifold-type engine, an injection nozzle, a fuel distributor connected to said nozzle, a fuel pump connected to said distributor, an electric motor driving said fuel pump, a bellows-type diaphragm responsive to engine manifold pressures, variable impedance means operatively connected to said diaphragm, and current conducting means connecting said electric motor and said impedance means.

6. In a fuel injection system for a manifold-type engine, a multiplicity of injection nozzles, a conduit connected to each nozzle, a fuel distributor having outlet ports communicating with the conduits, said distributor having an inlet port, means communicating said inlet port with said outlet ports in succession, a fuel pump separate from said distributor, a conduit connecting the pump outlet with a distributor inlet, an electric motor independent of the speed of said engine driving said fuel pump, a housing, a bellows-type diaphragm having one end thereof connected to said housing, said housing end being connectable to said engine manifold whereby said bellows diaphragm is responsive to manifold pressures, variable resistance means operatively connected to the opposite end of said bellows so as to be movable therewith, stationary contact means engaging said variable resistance means, and current conductor means connecting said stationary contact means to said electric motor, whereby the operation of said diaphragm in response to said manifold pressures will increase the output of said fuel pump at high manifold pressures and decrease the output of said pump at low manifold pressures.

7. In a fuel injection system for a manifold-type engine, an injection nozzle, a fuel pump connected to said nozzle, variable speed drive means independent of the speed of said engine for driving said pump, and means responsive to manifold pressure for varying the driving speed of said drive means.
